DESIGN FOR A BUILDING

J. Harry Shale and Louis C. Voelker, Rochester,
N. Y.; said Voelker assignor to said Shale,
doing business as Rochester Grills, Rochester,
N. Y.

Application April 27, 1938, Serial No. 76,772

Term of patent 14 years

To all whom it may concern:

Be it known that we, J. Harry Shale and Louis C. Voelker, citizens of the United States, residing at Rochester, in the county of Monroe and State of New York, have invented a new, original, and ornamental Design for a Building, of which the following is a specification, reference being had to the accompanying drawing, forming a part thereof.

The rear side of the building is substantially plain.

We claim:

The ornamental design for a building, as shown and described.

J. HARRY SHALE.
LOUIS C. VOELKER.
